Primary Examiner — Jennifer L Rempfer*Assistant Examiner* — Bethany Louise Mallino(74) *Attorney, Agent, or Firm* — John M. Lipchitz(57) **CLAIM**

The ornamental design for a shaving razor stand, as shown and described.

DESCRIPTION

FIG. 1 is a first perspective view of a shaving razor stand showing our new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines are directed to the environmental subject matter and form no part of the claimed design.
